UNITED STATES PATENT OFFICE.

THOMAS O. PERRY, OF TECUMSEH, MICHIGAN.

IMPROVEMENT IN WINDMILLS.

Specification forming part of Letters Patent No. **146,548**, dated January 20, 1874; application filed June 23, 1873.

To all whom it may concern:

Be it known that I, THOS. O. PERRY, of Tecumseh, in the county of Lenawee and State of Michigan, have invented certain Improvements in Windmills, of which the following is a specification:

My invention relates to that class of windmills which revolve horizontally on vertical shafts, and have wings which also revolve on vertical axes; it consists, first, in the adaptation of a vane to regulating the wings, by causing them to revolve on their own vertical axes in such a manner as to present their faces to the wind advantageously in every position; second, in the application of a governor, so regulating the speed of the mill as to give it an uniform velocity in varying winds, thus securing it against injury, and making it better adapted to driving machinery; third, in various accessory devices.

In the drawing, Figure 1 is a general plan of the mill, omitting, for perspicuity, the vane *v* and that portion of the governor shown in Figs. 4 and 5 below the vane *v* and above the central toothed-wheel *o*. Fig. 2 is an elevation of Fig. 1, projected in the direction A B, omitting the parts obviously not shown nor indicated by the letters. Fig. 3 is an elevation of Fig. 1, projected in the direction C D, showing also the pipe *l* and vane *v* in their true position, and omitting certain parts obviously not shown nor indicated by the letters. Fig. 4 shows in elevation that part part of the governor omitted in Figs. 1, 2, and 3, projected in a direction perpendicular to the face of the vane *v*; but the rods *r r* and piece *e*, also shown in Figs. 1 and 2, revolve with the mill, and may be in any position with reference to the vane. Fig. 5 is a plan of Fig. 4. Fig. 6 is a plan of the piece *e*. Fig. 7 is a plan of the weight *w*. Fig. 8 is a sectional elevation of Fig. 4. Fig. 9 is a plan of the vane *v*. Fig. 10 is an elevation of the pulley *p*, showing the spiral part in position. Fig. 11 is a plan of the crank *k'*, showing the oblong hole for the crank-pin to work in. Fig. 12 is a plan of the piece *l'*. Fig. 13 is a plan of the piece *b*.

If, in Fig. 1, disregarding the governor, the central toothed-wheel *o* be in any manner fixed to and held in position by the vane *v*, shown in Fig. 3, while the wind blows from A to B,

the connection between the vane *v* and wings *f' f''*, made by means of the toothed-wheels *o n n' m m'*, cranks *k k'*, ring *c*, small arms *a a'*, braces *b' b''*, and cranks *k' k''*, on the axes of the wings, will constitute the first part of my invention. Thus the motion of the cranks *k k'*, on the wheels *m m'*, is imparted to the cranks *k' k''* by means of the ring *c*, small arms *a a'*, and braces *b' b''*. The wings having once been set in position with reference to the vane, as shown in Fig. 1, by means of the nuts under the cranks *k' k''*, will successively assume, as the mill revolves, the positions shown, each wing making an angle of ninety degrees with the direction of the wind on arriving at D, forty-five degrees on arriving at A and B, and zero on arriving at C, while in all intermediate positions also the wings receive the wind advantageously. The wings revolve on their own axes in a direction opposite to that of the mill, the mill making two revolutions to one of the wing.

Though but four wings are represented in the drawing, the device is equally applicable to any number, the application of more or less wings only making a difference in the number of arms *a a' a''*. In all cases the wings are put in working order by turning the mill, and bringing each wing in succession to the position indicated by D, and there setting its face perpendicular to the vane *v*, by means of the nuts on the axes just under the cranks *k' k''*, which also screw on the ends of the axes. The number of wings used makes no modifications in the governors hereafter described. The wheels *m'* and *n'* may be omitted, being but duplicates of *m* and *n*, and are added for supporting one end of the ring *c*, and partly relieving the strain on *m* and *n*. The five toothed wheels *o m n m' n'* may all be placed in a straight line, but are placed as shown in the drawing for the purpose of putting them all upon the piece *d*, to which the arms *a a''* are bolted. The axes of the wings revolve in bearings inserted in the arms *a a''*, which are bolted to the pieces *d d'* fixed to the shaft *S*. The arms *a a''* should be braced together, so that the bearings will be kept firmly in their relative positions. In order that the springing of the axes of the wings may not cause the cranks *k' k''* to bind, the crank-pin is fixed to

the small arm *a*, and works in an oblong hole in the crank, shown in Fig. 11.

The governor.—If the vane *v* of the mill be caused to make a quarter revolution from its working position—*i. e.*, be turned in either direction, so as to make an angle of ninety degrees with the direction of the wind—each wing would be turned through one-eighth of a circumference, causing the wings on each side of the line A B to receive the wind equally, and the mill would stand still; or if the vane remain in position where the wind holds it, while the central toothed-wheel *o* is caused to make a quarter revolution, the same effect is produced. If the toothed wheel *o* makes less than a quarter-revolution, with reference to the vane, the wings are partially turned out of their working position, so as to take the wind at less advantage, and the motion of the mill is checked. Hence the governor is a device for causing the central toothed wheel *o* to make a partial revolution with reference to the vane. This is effected either by centrifugal force or by the direct force of the wind, as follows:

The small shaft *s* is either inserted into the large shaft *S* or screwed into the piece *d*. The piece of gas-pipe *l*, Figs. 4 and 8, is fixed to the central wheel *o*, and both turn freely on the small shaft *s*. The piece *i* is fixed to the pipe *l*. The drum *h*, piece *h'*, and vane *v* are fixed together, and are loose on the pipe *l*. The weight *w* is suspended by the chains *q q*, which pass over the pulleys *t t*, and fasten to the drum *h*, on which they wind when the weight is raised. The pipe *l* passes freely through the weight, allowing the weight to rise without obstruction, as also do the pieces *J J*, which are fixed to the piece *i*, and prevent the weight from turning and throwing the chains out of a perpendicular. As the weight rises, the chains *q q* pass over the pulleys *t t*, and wind on the drum *h*, thus allowing the pieces *i l w* and central wheel *o*, which turn together, to change position with reference to the vane, as required, for checking or stopping the mill.

For raising the weight *w*, two rods, *r r*, which slide freely up and down through holes in the pieces *d d'*, are attached at their upper ends to the piece *e*, which revolves with the mill beneath the weight. To the rods *r r*, Fig. 2, is attached a piece, *l'*, to which are attached chains *y y*, which pass over the pulleys *p p* and fasten to the ends of the horizontal rods *r' r'*, to the other ends of which, at the extremities of the arms *a' a''*, are fastened the governor balls *g g*. The centrifugal force of these balls causes the rods *r' r'* to roll horizontally over the pulleys *z z*, thus lifting the piece *l'*, rods *r r*, and piece *e*, which in turn lifts the weight *w*. Shoulders on the rods *r' r'*, coming in contact with the pieces *u u*, prevent the balls *g g* being thrown out farther than is necessary for stopping the mill. The piece *e* may be made to assist, also, in holding the weight *w* down, by means of a flange at the lower end of the piece *w'*, Fig. 8, which loosely encircles the pipe *l*, passes freely through *e*, and screws into

the weight *w*. The piece *i* is kept from turning too far in either direction by the horizontal and vertical pins shown at *x x*, Figs. 4 and 5. The pulleys *t t* should be shielded to prevent the chains from running off, as also should the pulleys *p p* and *z z*. The weight of the vane and drum *h* is supported by the cap *c'*, Figs. 4, 5, and 8, which rests on the top of the shaft *s*, the object being to leave the piece *i*, and parts connected therewith, free to turn unimpeded by the weight of the vane when the governor acts. To *h'*, Fig. 4, a funnel-shaped tin cover may be attached, so as to protect the toothed wheels and other parts from the weather.

In order that the mill may run with an uniform velocity in winds of varying force, there must be, for a particular speed of the mill, an exact balance between the weight which is to be raised and the force which raises the weight, for every position of the balls *g g*. If *p p* were common pulleys this balance would not be established, since the centrifugal force of the balls *g g* increases as their distance from the center of the mill increases. Therefore, instead of the ordinary pulley, *p* is made with a circular groove on one side and a spiral groove on the other, as shown in Figs. 2 and 10. The perpendicular chain *y* is fastened to a pin or screw on the circular part, and the chain connected to the rod *r'* winds around and fastens to the pin on the spiral part of *p*, so that, as the ball *g* increases its distance from the shaft of the mill, the chain unwinds from the spiral part of the pulley, causing the increasing centrifugal force of the balls to be counterbalanced by acting with a proportionately-decreasing leverage, so as to always balance the weight, which is a constant force acting with a constant leverage, since the chain *y* winds upon the circular part of *p*.

The required form of the spiral must be computed or determined by experiment. In the drawing the spiral is exaggerated. By placing additional weights upon the piece *l'*, Figs. 2 and 12, the weight to be raised will be increased, so as to require a greater speed of the mill in order to throw out the balls *g g*. Thus, by making the original weight sufficiently light, the speed of the mill may be controlled at will. The piece *b*, Figs. 2 and 13, to which the lower ends of the rods *r r* are secured, affords a means of raising the weight and stopping the mill at pleasure, by means of the lever *B* and rope *j*, operated from the ground. Any means of causing the central toothed wheel *o* to revolve out of its working position, with reference to the vane *v*, will stop or check the motion of the mill. Therefore, instead of using the balls *g g* for this purpose, a small wing at the end of a short lever-arm, making an angle (say ninety degrees) with the vane and clamped on to the pipe *l*, may receive the wind, so as to turn the central toothed wheel *o* and govern the mill. The arm of this small wing may be attached to the piece *i*, instead of the pipe, or to any other part inflexibly connected

with the central toothed wheel o . In the drawing, Figs. 4 and 5, the pipe l extends loosely through the drum h and vane v , and projects sufficiently above the vane for allowing the short lever-arm s , Fig. 5, to be clamped on just under the cap c . The small wing l'' is attached to the end of the arm s , so as to be blown around when the wind is sufficiently strong to raise the weight w ; for the weight is raised by the turning of the piece i , which is fixed to the pipe l . A very strong wind would force the wing l'' and arm s into a position parallel, or nearly so, with the vane, and stop the mill until the force of the wind should diminish. This form of governor, being less expensive, I contemplate using where the nature of the work will permit. If the governor first described be used, the pipe l need not extend higher than the piece i , in which case, the vane and drum h will be placed directly on the shaft S .

Experience has shown that neither the small wing l'' nor the governor-balls $g g$ are necessary to keep the mill from running at an injurious speed, since the increasing friction of the wings' axes against their bearings, due to centrifugal force, as well as the action of the wind upon the wings, will cause the weight w to rise and check the speed of the mill, provided the weight is not made too heavy. Thus, it appears that the flexible connection between the vane v and central toothed wheel o , made

by means of the weight w , &c., as before described, constitutes in itself a governor which is sufficient to insure the mill against attaining an injurious speed.

The vertical shaft S , to which the mill is attached, may extend downward as far as is desirable, and may be made to drive machinery, by means of gearing or belting, in any manner known to mechanics.

I claim as my invention—

1. The combination, with the vane v and wings $f' f''$, of the toothed wheels $o n n' m m'$, ring c , crank $k k' k''$, and small arms $a a$, substantially as and for the purpose hereinbefore set forth.

2. The combination, with the vane v and central toothed wheel o , of the weight w , pipe l , chains $q q$, pulleys $t t$, pieces i and $J J$, and drum h , substantially as and for the purpose set forth.

3. The piece e , in combination with the rods $r r$, pieces b and l' , for lifting the weight w , as described.

4. The governor-balls $g g$, in combination with the rods $r' r'$, chains $y y$, pulleys $p p$, piece l' , rods $r r$, and piece e , substantially as and for the purpose set forth.

THOMAS OSBORN PERRY.
